United States Patent Office.

EDWIN NORTON, OF BROOKLYN, NEW YORK, ASSIGNOR TO HIMSELF AND O. W. NORTON, OF SAME PLACE.

Letters Patent No. 92,538, dated July 13, 1869.

IMPROVED SPICE-CAN.

The Schedule referred to in these Letters Patent and making part of the same.

To all whom it may concern:

Be it known that I, EDWIN NORTON, of Brooklyn, in the county of Kings, and State of New York, have invented a new and useful Improvement in Spice-Cans; and I do hereby declare that the following is a full, clear, and exact description thereof, which will enable others skilled in the art to make and use the same, reference being had to the accompanying drawings, forming part of this specification.

This invention relates to improvements in packing-cans for spices, having for its object to provide a simple and cheap arrangement of the same, whereby the contents may be permanently and securely enclosed, as long as required, for shipment and for storage, and by a slight change, readily made, the said cans may be adapted for the delivery of the contents, through a perforated cover, in a separating and distributing way, as is required for culinary purposes.

Figure 1 represents a sectional elevation of a can constructed according to my improvement, and

Figure 2 represents a top view of the same.

Similar letters of reference indicate corresponding parts.

A represents the body of the can, and B, the cover, which is removable and perforated for sifting or distributing the contents by showering. These parts are constructed in the common way.

My invention consists in combining, with the said cans, stiff paper disks B, or disks of other similar substance, by pressing them into the covers B, so as to fit snugly and adhere by friction in the position represented in the drawings, to prevent the contents of the box from escaping through the perforations while not required for use.

These paper disks are applied when the boxes are

made, and may be best done at the time of stamping up the covers, being pressed in by the forming-punch; but if preferred, they may be applied by a separate operation.

When it is required to use the contents out of the boxes, the tin covers B are removed, the paper disks taken out, and the tin covers replaced, when the cans are in the proper condition for sifting or distributing the contents, as required.

I am aware that cans with a large opening through the top, and covered with paper, to be punched for delivering the contents, have been used, but these are objectionable, because the walls of the punctures must be necessarily rough and jagged, causing the contents of the cans to adhere and close the punctures. Moreover, the paper, having no protection over these large holes, is liable to be broken through.

I am also aware that cans with permanent perforated tops and removable close covers of tin or other metal have been used, but these are much more expensive than mine.

Having thus described my invention,

What I claim as new, and desire to secure by Letters Patent, is—

The combination, with the body A and perforated removable cap B, of paper disks C, or disks of other similar substance, when arranged substantially as specified.

The above specification of my invention signed by me, this 8th day of June, 1869.

EDWIN NORTON.
